WELL PACKER

Claude C. Taylor, Long Beach, and Edgar W. McGaffey, Oildale, Calif., assignors, by direct and mesne assignments, to McGaffey-Taylor Corporation, Long Beach, Calif., a corporation of California

Application January 30, 1945, Serial No. 575,252

11 Claims. (Cl. 166—12)

1

This invention relates to a tool for use in packing off cased oil wells.

It is known to provide a tool for use in cased wells, comprising a packer adapted to be secured to a tubing string and arranged to seal between the casing and the tubing by pressure trapped below the packer. Such a tool also is provided with casing gripping means adapted to grip the casing in response to upward movement of the packer relative to the tubing or downward movement of the tubing relative to the packer.

With a tool arranged in this manner, the weight of the tubing string acts in opposition to the excess well pressure trapped below the packer, to cause the casing gripping means or slip mechanism to grip the casing. At the same time, the well pressure acts on the tubing string to lift it, and thereby reduces the effective weight exerted by the tubing to expand the slip mechanism.

It is an object of this invention to provide such a tool wherein the excess well pressure below the packer has no tendency to loosen the slips or casing gripping means, or to raise the tool.

It is another object of this invention to provide such a tool wherein the excess well pressure below the packer exerts a downward force on the tubing string.

It is another object of this invention to provide such a tool wherein the excess well pressure below the packer exerts a force urging the slips to expanded condition in assisting relation to the force exerted by the packer for such purpose.

In the tools of the character under discussion, it is usual to provide means, optionally operable, to form a by-pass around the packer. It is another object of this invention to provide such a tool wherein the by-pass can be opened without the necessity of downward movement of any part of the tool.

Tools of the character under discussion are extensively used in the pressure cementing of wells. In such an operation, cement slurry is forced down the tubing string and out the lower end thereof into the casing, the packer serving to prevent passage of the cement upwardly in the casing exteriorly of the tubing. The cement is thus obliged to pass out of the casing through appropriate openings in the casing into the formation. In general, the removal of such tools upon completion of the cementing operation is difficult or even impossible. It is thus another object of this invention to provide a tool capable of use for pressure cementing and which

2

may be removed readily from the well upon completion of the cementing operation.

It is another object of this invention to provide such a tool wherein the excess cement may be removed after the cementing operation has been completed, without moving any part of the tool.

It is still another object of this invention to provide a tool of the character described in which excess pressure below the packer can be relieved without the necessity of withdrawing the tool.

It is a still further object of this invention to provide such a tool wherein no ports are necessary in the tubing string or extension thereof.

This invention possesses many other advantages, and has other objects which may be made more easily apparent from a consideration of one embodiment of the invention. For this purpose there is shown a form in the drawings accompanying and forming part of the present specification. This form, which illustrates the general principles of the invention, will now be described in detail; but it is to be understood that this detailed description is not to be taken in a limiting sense, since the scope of the invention is best defined by the appended claims.

Referring to the drawings:

Figure 1 is a vertical axial section, partly in elevation, of a tool incorporating the features of the invention in place in a well casing;

Figure 2 is a similar view, showing a different operating position of the parts.

Referring to the drawing, the tool 1 is shown as comprising an elongated body 2 which is adapted for insertion in a well casing 3, and is supported therein by a hollow mandrel 4 extending axially through the body 2. This body 2 is movable, angularly and axially, relative to the mandrel 4 to a limited extent. The mandrel 4 is secured to the lower end of a string of tubing or drill pipe 5 by a special coupling member 6. As is well understood, the tubing string 5 extends to the mouth of the well where it is supported and arranged for movement to manipulate the tool 1, as well as for connection to a source of fluid, cement slurry, or the like, as required. A downward extension of the tubing string 5 is provided by the tubing 5—a secured to the lower end of the mandrel 4 as by a coupling 4—a. The tubing 5—a may be of any desired length and is adapted to have suitable appliances, known in the well cementing art, attached at its lower end.

The tool 1 is provided with casing gripping means for restricting upward movement of the

tool in the casing 3. This means comprises a bowl 9 secured to the upper end of the body 2, having a plurality of openings 10 extending through its wall, in each of which a slip or casing gripping member 11 is mounted for movement toward and away from the casing 3. The slips 11 are slidably attached in a known manner to the upwardly and outwardly inclined surfaces 12 formed on a slip head 13, the slips 11 and the slip head 13 forming relatively movable members. When the slip head 13 is caused to move inwardly of the bowl 9, either by downward movement of the slip head, or upward movement of the bowl, or both, the slips 11 are expanded and urged outwardly to operative position, engaging the casing 3. When the slip head 13 moves outwardly of the bowl 9, the slips 11 are retracted to inoperative position, free of the casing. This is similar to the conventional slip arrangement sometimes known as a down drive spear.

The slip head 13 has a bore 14 slidably mounting the slip head on the upper end portion of the mandrel 4, a lost motion connection 15 being provided between the mandrel and the slip head. That is, an upper hollow extension 16 is secured to the slip head at 16-a, as by welding or in any other suitable manner. The upper end of this extension 16 terminates in an inwardly directed flange or lip 17 arranged to be engaged by an outwardly directed projection or flange 18 on the coupling 6. Engagement of the projections 17 and 18 (Figure 1) serves to limit relative movement between the slip head 13 and the mandrel 4 in one direction and engagement of the coupling 6 with the top of the slip head 13 (Figure 2) serves to limit such movement in the opposite direction.

The body 2 has a reduced portion 20 below the bowl 9 with a bore 21 slidably accommodating the mandrel 4. The body portion 20 has a bayonet slot 22 for receiving a pin 23 on the mandrel 4. When the pin 23 is in the transverse portion 22-a of the slot 22, the mandrel 4 is secured at its uppermost position with respect to the body 2, the flange 18 on coupling 6, by engaging the lip 17 on the slip head 13, serving to maintain the slip head in its outer position from the bowl 9, whereby the slips 11 are held in their retracted positions, (see Figure 1). By rotating the mandrel 4 a fraction of a turn clockwise (looking axially from above the mandrel), the pin 23 is positioned above the vertical portion 22-b of the slot 22, allowing the mandrel 4 to move downwardly in the body 2. Conventional bow springs 24 are provided on the body 2 which, by engagement with the casing, restrain the body 2 against movement during such unlocking operation, and until the slips 11 initially engage the casing.

The body 2 has a lower extension 26 which carries the packer forming means 27, and is provided with a bore 28 through which the mandrel 4 passes. The extension 26 has a threaded neck 29 by which it is secured to the upper portion 30 of the body 2 and which neck carries the packer 27. This packer 27 is of conventional form and is shown as comprising a pair of inverted cup members 31 and 32 of flexible material, having downwardly and outwardly directed annular lips 31-a and 32-a contacting the interior surface of the casing 3. Thus, with the packer restrained against upward movement, pressure below the packer urges the lips 31-a and 32-a outwardly into sealing relation with the casing 3.

The upper portion of the bore 28 is of reduced

diameter, forming a valve chamber 35. The lower end of the bore 28 is closed by a head 36 through which the mandrel 4 passes, a packing 37 being provided to prevent leakage of the fluid between the mandrel and the head. The mandrel 4 is provided with a piston or valve member 38 which may comprise a downwardly directed cup leather 39, which seals against the wall of the chamber 35 to prevent passage of fluid upwardly in the chamber past the piston 38.

A second piston or movable wall 40 is secured on the mandrel 4 in spaced relation below the piston 38, and may comprise an upwardly directed cup leather 41, which seals against the wall of the lower portion or working chamber 42 of the bore 28, to prevent passage of fluid downwardly in the chamber 42 past the piston 40. The chamber 42 is thus an expansible pressure chamber.

The pistons 38 and 40 cooperate with the bore 28 to form a closed pressure space or expansible chamber 43 between the pistons. A port 45 near the upper end of the chamber 42 places the space or chamber 43 in constant communication with the interior of the casing 3 below the packer 27. Thus, due to the larger area of the piston 40 as compared with the piston 38, any well pressure above the packer 27 in excess of the pressure above the mandrel 4 and the attached tubing string 5 downwardly with respect to the packer.

When it is desired to run the tool into the well, a novel by-pass arrangement permits flow of fluid from one side of the packer to the other, to prevent tearing of the packers. Additionally, preliminary pumping down of cement, and washing of the excess cement from the tool are readily performed by the provision of such a bypass. Thus, means are provided whereby the space 43 may be optionally placed in communication with the interior of the casing 3 above the packer 27, thereby forming a bypass around the packer. For this purpose a port 46 is provided through the body 2, above the packer 27, into the valve chamber 35, and positioned so as to be traversed by the piston 38 near the upper end of its stroke.

To permit control of the bypass and additionally to control the pressure conditions in the space 43, an equalizing port 47 is provided, which communicates with the working chamber 42 near its lower end and enters the valve chamber 35 through an access port 47-a so located as to be traversed by the piston 38 near the lower end of its stroke. The piston 38 thus cooperates with the ports 46 and 47 to form a valve controlling the pressure in the space 43. With the mandrel 4 and the piston 38 at their upper positions in the body 2 (Figure 1), the pressure space 43 is in communication with the interior of the casing 3 above and below the packer 27, since the ports 45 and 46 are both open to the space 43. Further, the pressures on opposite sides of the piston 40 are equal, since the port 47 connects the space 43 with that portion of the chamber 42 below the piston. Upon movement of the mandrel 4 and the piston 38 to their lower positions (Figure 2), communication between the ports 45 and 46 is interrupted, closing the bypass around the packer. The ports 46 and 47-a are in communication, via the valve chamber 35 above the piston 38; thus pressure in the chamber 42 below the piston 40 is equal to the well pressure above the packer. The pressure in the working space 43 is equal to the well pressure below the packer 27, due to the port 45. Thus, excess pressure below the packer acts on the piston 40 to urge

the mandrel 4 and tubing string 5 downwardly, with reference to the packer and slip assembly, thereby avoiding any tendency of such pressure to urge the mandrel upwardly and release the slips 11.

The operation of the tool may be briefly summarized as follows: the tool is lowered into the well with the tool connected to the tubing string 5, and locked with the body 2 in its lower, slip retracted position on the mandrel 4, by engagement of the pin 23 with the transverse part 22-a of the bayonet slot 22 (as shown in Figure 1). In this position the ports 45 and 46 cooperate to form a bypass around the packer 27; thus no fluid is trapped below the packer and the tool can be lowered freely in the casing to the desired depth. Cement slurry is then pumped down the tubing string 5 until it reaches the tool. The tubing string 5 is then turned to align the pin 23 with the vertical portion 22-b of the bayonet slot 22, and the tubing lowered further, which sets the slips 11 to engage the casing 3 and closes the bypass around the packer 27. This position is shown in Figure 2. The pumping of cement slurry from the surface through the tubing 5 is then resumed and the slurry forced down and out the lower end of the tubing extension 5-a into the area to be cemented off under pressure.

Upward movement of the tool or drill pipe as the pressure is built up below the packer 27 is prevented, since any slight upward movement of the body 2, due to the pressure on the packer 27, exerts a pressure against the slips 11 and urges them upwardly of slip head 13, tightening their contact against the casing. Further, the pressure built up below the packer 27 exerts, through the port 45, a downward pressure on the piston 40, since the space in the chamber 42 below the piston 40 is equalized to well pressure that exists above the packer 27 through the ports 47, 47-a and 48, as previously explained. The effective area of the piston 40 is sufficiently greater than the piston 38, so that the piston 40 exerts a downward pull on the mandrel 4 and the slip head 13, overcoming any "popping up" tendency of the mandrel 4 and connected parts, due to excess pressure below the packer 27.

As the pressure increases below the packer 27, upward force against the slips 11 increases and downward pressure against the mandrel 4 and the slip head 13 also increases, thereby increasing the locking effect of the slips 11 against either upward or downward movement.

After the desired amount of cement has been placed, it is necessary to remove and circulate out of the well any excess cement that may still remain in the tubing string or in the tool. This is readily accomplished by any one of several procedures.

For example, the tool 1 can be left in cementing position and "back scuttling" used, that is, water from the surface pumped down the casing 3, outside the tubing string, past the compressible packer 27 and the tool 1, into the bottom end of the tube 5-a, thence up to the surface through the tube 5-a, mandrel 4, and the tubing string 5 until the inside of the casing 3 and the tool 1 are cleared of cement.

Another method is as follows: after cementing pressure is released, the tubing string 5 is raised a distance which is sufficient to pull the slip head 13 out of pressure engagement with the slips 11 and place the slips 11 in a retracted position with regards to the casing 3. This movement also serves to move the pin 23 up-

wardly in the slot 22-b of the bayonet slot 22 into alignment with the transverse portion 22-a thereof. The tubing string is then turned counterclockwise, engaging the pin 23 in the transverse portion 22-a of the bayonet slot, and locking the body in its lower slip retracted position, as shown in Figure 1. Cleaning fluid, such as water, is then pumped down the tubing 5, mandrel 4 and out the lower end of the extension 5-a into the interior of the casing 3. Thence the fluid returns upwardly in the casing 3 to the tool 1, past the packer 27 via the ports 45 and 46, and to the mouth of the well.

Still another method, which is perhaps simplest and more preferable, is as follows: raise the tubing string 5 to place the tool 1 in the position of Figure 1, opening the bypass around the packer 27, and "backscuttle" or force fluid down the casing 3, past the packer 27 via the bypass provided by the ports 45 and 46, into the lower end of the tubing 5-a and thence via the mandrel 4 and the tubing string 5 to the mouth of the well. In this case it is not necessary to lock the slips in retracted position as before described, since there will be no tendency to force the packer 27 and the tool 1 upwardly.

We claim:

1. A tool for use in a well bore having a casing, comprising: a body; means forming a packer on said body for sealing against the casing to prevent flow of fluid upwardly between the body and the casing; casing gripping means on said body operable to prevent upward movement of the body and packer in the casing; a tubular mandrel extending axially through the body and adapted to be secured to a tubing string, said mandrel being movable with respect to the body; means movably mounted on the mandrel for operating said casing gripping means whereby said relative movement in one direction between said mandrel and said body operates said casing gripping means; means carried by said body frictionally engaging the casing to restrain movement of the body therein; means forming a releasable lock between the mandrel and the body preventing relative movement therebetween in a direction to operate said casing gripping means, a pair of elements forming a pressure responsive assembly, said elements comprising a piston and cylinder, means connecting one of said elements to the mandrel and the other of said elements to the body; and means in the body maintaining communication between the interior of the casing below the packer outside the tool and the interior of the cylinder on one side of the piston whereby fluid pressure below the packer exerts a force on said mandrel to cause relative movement between said mandrel and said body in a direction to operate said casing gripping means.

2. A tool for use in a well bore having a casing, comprising: a body; means forming a packer on said body for sealing against the casing to prevent flow of fluid upwardly between the body and the casing; casing gripping means on said body operable to prevent upward movement of the body and packer in the casing; a tubular mandrel extending axially through the body and adapted to be secured to a tubing string, said mandrel being movable with respect to the body; means movably mounted on the mandrel for operating said casing gripping means whereby relative movement in one direction between said mandrel and said body operates said casing gripping means; means carried by said body fric-

tionally engaging the casing to restrain movement of the body therein; means forming a releasable lock between the mandrel and the body preventing relative movement therebetween in a direction to operate said casing gripping means; a piston and cylinder assembly connected with said mandrel and said body, said piston being connected to the mandrel; and means in the body forming a passage between the interior of said cylinder above the piston and the interior of the casing below the packer outside the tool, whereby fluid pressure in the casing below the packer urges movement between said mandrel and said body in a direction to operate said casing gripping means.

3. A tool for use in a well bore having a casing, comprising: a body; means forming a packer on said body for sealing against the casing to prevent flow of fluid upwardly between the body and the casing; casing gripping means on said body operable to prevent upward movement of the body and packer in the casing; a tubular mandrel extending axially through the body and adapted to be secured to a tubing string, said mandrel being movable with respect to the body; said casing gripping means comprising a pair of relatively movable members, connected together and connected respectively for movement with the body and with the mandrel whereby relative movement between the mandrel and the body will operate said casing gripping means; means carried by said body frictionally engaging the casing to restrain movement of the body therein; means forming a releasable lock between the mandrel and the body preventing relative movement therebetween in a direction to operate said casing gripping means; means forming a cylinder in said body; a piston within said cylinder, cooperating therewith to form an expandable pressure chamber and secured to said mandrel; means in said body maintaining communication between the interior of the casing below the packer and said chamber; means in the body for establishing communication between said chamber and the interior of the casing above said packer; and means on the mandrel, operable for interrupting said last mentioned communication upon movement of said mandrel to operate the casing gripping means.

4. A well packer for use in a well bore having a casing and adapted to be secured to the lower end of a tubing string, comprising: a packing device; casing gripping means connected to said packing device for preventing upward movement of said device in the casing; said casing gripping means comprising slips and a slip head, said slips and said slip head forming relatively movable members, relative movement therebetween serving to operate the slips to engage the casing; means movably carried by the packing device for operating said casing gripping means to cause said slips to engage the casing in response to downward movement of said tubing string in the casing; lock means forming a releasable lock between the means for operating the casing gripping means and the packing device for optionally preventing operation of said casing gripping means; a cylinder carried by the packing device and piston assembly within said cylinder, cooperating to form expandable pressure chambers on opposite sides of the piston; means in the cylinder establishing communication between one of said chambers and the interior of the casing below the packing device; means in the cylinder establishing communication between the other

of said chambers and the interior of the casing above the packing device outside the well packer; means attached to the piston connected with one of said movable members for movement with said piston; and means on the cylinder connecting the other of said members for movement with said cylinder, whereby increase of pressure in the interior of the casing below said packing device relative to the pressure in the interior of the casing above the packing device, urges operation of said casing gripping means to cause said slips to engage the casing.

5. A tool for use in a well bore having a casing, comprising a body, means forming a packer on said body for sealing against the casing to prevent flow of fluid upwardly between the body and the casing, slips on the body for gripping the casing and preventing upward movement of the body and the packer in the casing, a tubular mandrel adapted to be secured to a tubing string, extending axially through the body and movable with respect thereto, a slip head movable with respect to the body and adapted to operate the slips to casing gripping position in response to downward movement of the slip head relative to the body, means connecting said slip head to said mandrel permitting limited axial movement of said mandrel with respect to said slip head, means carried by said body frictionally engaging the casing to restrain movement of the body therein, means releasably securing said mandrel to said body against slip operating movement, means forming a pair of expandable pressure chambers connected to said body to move therewith and separated by a movable wall secured to said mandrel, one of said chambers being in continuous communication with the interior of the casing below the packer, port forming means in said one chamber in communication with the interior of the casing above the packer; means carried by said mandrel for controlling said port forming means in accordance with the position of said mandrel, and means on said body forming a port connecting said chambers and controlled by the means carried by said mandrel for establishing communication between the other of said pressure chambers and said port forming means, upon a predetermined downward movement of said mandrel relative to said body; the connecting means between the slip head and the mandrel preventing operation of the slips to casing gripping position until after the interruption of communication between said one of said chambers and the interior of the casing above the packer and the establishment of communication between said other of said chambers and the interior of the casing above the packer.

6. In a pressure actuated mechanism; means forming a pair of coaxial cylinders of different diameters, secured to each other and freely communicating at their adjacent ends; a pair of pistons respectively in said cylinders; means securing said pistons in fixed axial relationship; means for establishing communication between the interior of one of said cylinders at that end adjacent the other cylinder with a source of pressure; means for establishing communication between the interiors of the remote ends of the cylinders with another source of pressure, said sources providing different pressures, whereby relative movement between the cylinders and pistons is caused, said last mentioned communication forming means including a port so spaced from the end of one of said cylinders as to be traversed by the piston therein as the piston

approaches the end of its stroke whereby to establish communication between said pressure sources.

7. A tool for use in a well bore having a casing, comprising: a body; a packer on said body for sealing against the casing; casing gripping members on the body for preventing upward movement of the body and packer in the casing; a member movably mounted on said tool for movement with respect to the body for operating the casing gripping members to grip the casing; a mandrel mounting said body for movement relative thereto, means on said mandrel engageable with and adapted to move said movably mounted member upon movement of said mandrel relative to said body; said mandrel being adapted for connection with a tubing string and movable therewith relative to said body to cause said movably mounted member to operate said casing gripping members to grip the casing; means on the body frictionally engageable with the casing to restrain movement of the body therein; means releasably connecting said mandrel with said body against relative movement therebetween for preventing operating movement of said movably mounted member with respect to the body and retaining the casing gripping members in inoperative condition; and means sealing between said mandrel and said body.

8. A tool for use in a well bore having a casing, comprising a body; a packer on said body for sealing against the casing; members on the body for gripping the casing to prevent upward movement of the body and packer in the casing; a member movably mounted on said tool for movement with respect to the body for operating the casing gripping members to grip the casing; a mandrel mounting said body for movement relative thereto, means on said mandrel engageable with and adapted to move said movably mounted member upon movement of said mandrel relative to said body; said mandrel being adapted for connection with a tubing string for movement therewith relative to said body; means on the body frictionally engageable with the casing to restrain movement of the body therein; means releasably connecting said body with said mandrel against relative movement therebetween for preventing operating movement of said movably mounted member with respect to the body and retaining the casing gripping members in inoperative condition; and fluid pressure means comprising a pair of relatively movable elements connected respectively to said mandrel and said body to exert a force urging relative movement between said movable elements.

9. A tool for use in a well bore having a casing, comprising: a body; a packer on said body for sealing against the casing; casing gripping members on the body for gripping the casing to prevent upward movement of the body and packer in the casing; a member movably mounted on said tool for movement with respect to the body for operating the casing gripping members to grip the casing; a mandrel mounting said body for movement relative thereto and engageable with and adapted to move said movably mounted member; said mandrel being adapted for connection with a tubing string for movement therewith; means on the body frictionally engageable with the casing to restrain movement of the body therein; means releasably connecting said body and said mandrel

against relative movement for preventing operating movement of said movably mounted member with respect to the body and retaining the casing gripping members in inoperative condition; means on the lower end of said body forming a bore, closed at its ends; means forming a movable wall in said bore cooperating therewith to form a pair of expandable pressure chambers; said movable wall being connected to the mandrel; and means forming communications respectively between the interior of the casing on opposite sides of the packer and said chambers, whereby excess pressure on one side of said packer exerts a force on said mandrel to operate said movably mounted member to urge said casing gripping members in casing gripping direction.

10. A tool for use in a well bore having a casing, comprising: a body, a packer on said body for sealing against the casing; members on the body for gripping the casing to prevent upward movement of the body and packer in the casing; a member movably mounted on said tool for movement with respect to the body, for operating the casing gripping members to grip the casing; a mandrel mounting said body for movement relative thereto, means on said mandrel engageable with and adapted to move said movably mounted member upon movement of said mandrel relative to said body; said mandrel being adapted for connection with a tubing string to move therewith relative to said body; means on the body frictionally engageable with the casing to restrain movement of the body therein; means releasably connecting said body with said mandrel against relative movement therebetween for preventing operating movement of said movably mounted member with respect to the body and retaining the casing gripping members in inoperative condition; and a cylinder and piston assembly connecting said body and said mandrel, the interior of the cylinder on one side of the piston being communicative with the interior of the casing on one side of the packer, the interior of the cylinder on the opposite side of the piston having a port adapted to be connected with a source of pressure differing from that in said casing interior, whereby said difference in pressure will exert a force on said mandrel to cause said movably mounted member to urge said casing gripping members in casing gripping direction.

11. A tool for use in a well bore having a casing, comprising: a tubular body; a packer on said body for sealing against the casing; a member movable axially of the body and adapted for connection with a tubing string; slips carried by said body for engaging the casing to prevent upward movement of the body and packer therein; a slip head movably mounted on said tool for movement with respect to the body in a direction axially thereof, for operating the slips to grip the casing; means forming a by-pass in said body for passing fluid between the interior of the casing above the packer and the interior of the casing below the packer, comprising a pair of axially spaced ports through the wall of the body; means carried by said member within said body for interrupting communication between said ports and controlling said by-pass in accordance with the position of said member with respect to the body; and means carried on said member forming a lost motion connection between said slip head and said member operable by the same

movement to cause by-pass closing movement of
said member and to operate the slips.
